UNITED STATES PATENT OFFICE

1,936,336

ATHLETIC GIRDLE

Joseph Louis Montmarquet, Caldwell, N. J.

Application June 10, 1931. Serial No. 543,351

3 Claims. (Cl. 128—167)

This invention relates to athletic apparel, particularly that to be worn by women.

It is an object of my invention to provide a garment to be worn, particularly by women, during occupation in sports, to give them, during such strenuous activity, the requisite freedom of the limbs and the rest of the body, and at the same time properly support the abdominal cavity to assure the wearer confidence and freedom from injury during indulgence in such activity.

Any attempts to utilize the present day girdles and abdominal supports during strenuous activity, as that involved in sports, have not benefited the wearer in that they interfere with the freedom of the body and involve the use of elastic elements which fail to give proper support and pressure at the desired portions of the body.

It is therefore an object of my invention to provide an athletic garment, particularly useful for women engaged in athletic activities, which may be conveniently and comfortably worn, without limiting the movement of the wearer, and which gives the necessary character of support to the sub-umbilical abdominal region, and pressure to the groin portion, leaving the limbs and upper umbilical region free and unconfined for proper athletic movement.

It is further contemplated by my invention to provide a garment which will give the requisite pressure and support to the sub-umbilical region and pressure to the groin portion of a manner to leave the limbs and waist of the wearer free from restraint for proper athletic activity, not only useful for such intended purposes but also desirable to hide defects in appearance, due to obesity, especially when the wearers expose themselves for athletic activities, especially swimming or the like.

It is a further object of my invention to provide a garment which will give the requisite pressure and support to the sub-umbilical region and to the groin portion of the wearer, and at the same time provide a garment which prevents unsightliness due to gathering of garments in the crotch adjacent the buttocks during exercising, and further to provide a garment of the character referred to which will assure comfort and freedom from chafing, due to a tendency of garments during activity in athletics to gather in the crotch adjacent the buttocks.

Other objects of my invention therefore reside in the provision of an athletic garment which maintains the apparel of the wearer continuous over the crotch adjacent the buttocks and assures

the requisite comfort and support to women engaged in athletic activity.

To attain these objects and such further objects as may appear herein or be hereinafter pointed out, I make reference to the accompanying drawing forming a part hereof, in which—

Figure 1 is a profile view of a torso of a body, showing my device in use;

Figure 2 is an enlarged perspective view taken from a direction to the rear of the torso;

Figure 3 is a perspective view of my device;

Figure 4 is a front plan view of the device, as it appears flattened out;

Figure 5 is a section taken on the line 5—5 of Figure 4.

Making reference to the drawing, my device comprises an elastic belt 10, of a width to cover substantially the sub-umbilical region, preferably comprising a front section 11 and a rear section 12, sewn together at 13 and 14, the stitch lines whereof are preferably covered by a stiffening tape 15 and 16. From the frontal medial portion to the rear medial portion of the sections 11 and 12, respectively, there is connected two triangularly shaped pieces of fabric 17 and 18, respectively, the bases of which triangular pieces are sewn to the elastic sections 11 and 12, by the stitch lines 19 and 20, respectively, the apices whereof are joined by a narrow band 21. The altitude of the triangular portions is calculated to cooperate with the elastic belt 10, formed by the sections 11 and 12, to snugly fit the groin portion, and the width of the base of the triangular portion 17 at 22 is calculated to fit just between the left and right inferior-spine iliac crest.

I may make sections 17 and 18 of inelastic material, such as canton flannel. However, in order to secure additional advantages which will now be described, the triangular section 17 is made of fabric such as canton flannel, whereas the rear section 18 is made for a portion of its length of elastic knitted fabric with the elastic or grain running in a direction similar to the elastic fabric constituting the belt 10. Distension of the upper portion of the triangular section is in a direction along the belt, or transverse to the body, but is inelastic in a vertical direction when worn.

Though I have above described the sections 17 and 18 as constituting triangular sections joined at the apices thereof by a narrow band 21, it is preferred that a portion of the rear triangular section 18 be composed, for part of its length only, of elastic fabric, the remainder being of inelastic canton flannel, as shown at the sec-

tion 18', which adjoins the lowermost portion of the rear triangular section, attachment being made by the stitch line 18a. The elastic portion of the rear section constitutes about two-thirds of the length, whereas the inelastic section 18' constitutes about one-third of the triangular rear section of the garment.

The elastic fabric constituting the belt, and the sections 11 and 12, and the upper triangular rear portion 18, are made, preferably, of interwoven rubber filament and cotton or silk fabric, and positioned with elastic filaments, as previously indicated in the horizontal or transverse position. The upper portion 12 and section 18 may be integral, or may constitute two sections stitched to each other, without interfering with the elasticity of these parts.

By the construction shown, confining the elastic band above the hips and to the sub-umbilical region, the proper pressure is given to this part of the body without interfering with the freedom of the movement of the limbs.

The frontal triangular section 17 is suspended from the elastic webbing constituting the band, giving resilient suspension to the crotch member, and compensating for any tendency of a movement of the body to displace the crotch section at the front of the garment from its proper position. The semi-flexible stiffening strips 15 and 16 serve to maintain the garment in proper position.

Furthermore, making the front triangular section 17 of inelastic material immediately under the elastic suspension provided by the section 11 of the band, the requisite pressure tending to flatten the abdomen, as well as to the groin portion is thereby provided. Limitation of size of the triangular section 17 between the inferior spine iliac crests to the right and left, leaves the limbs free for proper activity.

By enlarging the section 18 as compared with the front section 17, and making the same for at least two-thirds of its length of elastic material distensible in a transverse direction, an additional desirable value is obtained. This construction serves to cover the crotch adjacent the buttocks of the wearer to form a continuous covering. The movement incident to exercising, such as by the bending of the body in a position shown in Figure 2, ordinarily tends to cause a gathering of the apparel worn by the individual into the crotch portion of the buttocks. By the construction as provided, however, distension of the section 18 in a transverse direction occurs, and does not bind the crotch portion to within the crotch of the wearer. This property of the garment to conform itself to the various positions of the wearer, particularly adjacent the buttocks, avoids the chafing and binding effect tending to cause discomfort to the wearer.

It will further be found that no adjustment of the clothes need be made after vigorous exercise,

when wearing my garment, as aforementioned, with the resilient rear section 18 as provided, and will be found exceedingly desirable when worn by women in bathing suits, or involved in aquatic activity, and the apparel usually worn under such circumstances. Outer garments which would ordinarily tend to present an unsightly appearance when clinging to the body, particularly at the crotch portion adjacent the buttocks, tending to additionally chafe the wearer, are maintained in proper and neat position by the device contemplated by my invention, in addition to providing the comfort due to proper support of the body, by reason of the construction and resiliency of the coordinating parts.

This application is a continuation in part of my application, S. N. 457,055, filed May 29, 1930.

Having thus described my invention and illustrated its use, what I claim as new and desire to secure by Letters Patent is—

1. In apparel of the character described, comprising a completely elastic encircling band of a width confined to the sub-umbilical region, and a diametrically connected crotch portion connected to the lower edge of said band, the front section of said crotch portion being formed of inelastic material to cover the region of the groin and extending to the crotch, the rear section of said crotch portion constituting for a major part of its length, transversely elastic fabric adapted to continuously cover the rear portion of the crotch, adjacent the buttocks.

2. In apparel of the character described, a completely encircling band of a width confined to the sub-umbilical region, comprising an elastic webbing material distensible in a direction of the waist of the wearer, a crotch member arranged to connect diametrically to said band to a lower edge of said band, said crotch member constituting triangularly formed sections, the front being of inelastic material, the rear being formed of elastic webbing distensible in a direction similar to the band, but otherwise inelastic in a vertical direction.

3. In apparel of the character described, a completely encircling band of a width confined to the sub-umbilical region, comprising an elastic webbing material distensible in a direction of the waist of the wearer, a crotch member arranged to connect diametrically to said band to a lower edge of said band, said crotch member constituting triangularly formed sections, the front being of inelastic material, the rear being formed of elastic webbing distensible in a direction similar to the band, but otherwise inelastic in a vertical direction, the rear triangular section being wider than the front section and arranged to cover the crotch of the wearer adjacent the buttocks.

JOSEPH L. MONTMARQUET.
